FIG. 1

FIG. 2

FIG. 3

FIG. 4

FIG. 5

FIG. 6

Fig. 1 is a perspective view of a household tool for cleaning food mixer bowls and beaters, showing my new design;

Fig. 2 is a top plan view;

Fig. 3 is a side elevational view;

Fig. 4 is a fragmentary, longitudinal sectional view taken along line 4—4 of Fig. 2;

Fig. 5 is a cross-sectional view taken along line 5—5 of Fig. 2; and

Fig. 6 is an enlarged end elevational view thereof.

The bottom, not shown, of the design is a mirror image of the top as seen in Figs. 1 and 2.

I claim:

The ornamental design for a household tool for cleaning food mixer bowls and beaters, as shown and described.
